[57] CLAIM

The ornamental design for an eyestay element set for a shoe, as shown and described.

DESCRIPTION

FIG. 1 is a left side elevational view of an eyestay element set of a shoe showing my new design;

FIG. 2 is a right side elevational view;

FIG. 3 is a sectional view taken on line 3—3 of FIG. 2;

FIG. 4 is a front elevational view; and

FIG. 5 is a top plan view.

The broken line showing of a shoe is for illustrative purposes only and forms no part of the claimed design.

FIG. 4

FIG. 5
